MINING MACHINE

Joseph F. Joy, Claremont, N. H., assignor to Sullivan Machinery Company, a corporation of Massachusetts

Application November 12, 1934, Serial No. 752,670

29 Claims. (Cl. 262—30)

This invention relates to mining machines, and more particularly has reference to improvements in coal mining machines of the continuous cutter, flexibly fed, floor type.

An object of this invention is to provide an improved coal mining machine. Another object is to provide an improved coal mining machine of the longwall, floor cutter type. Another object is to provide an improved coal mining machine having improved slot forming means whereby horizontal full depth slots may be cut in the coal face in either of two superimposed planes, near the level of the mine floor and a substantial distance above the floor level. A further object is to provide an improved coal mining machine of the flexibly fed, floor type having improved slot forming means in the form of an elongated extremely narrow cutter blade pivotally mounted on a rotatable cutter head and rotatable with the cutter head about the head axis into different cutting positions, and having embodied therein improved head rotating and cutter blade swinging means. Yet another object is to provide an improved floor type coal mining machine of an unusually narrow, compact design, having improved slot forming means whereby a machine of an extremely small size, much smaller than a standard heavy bar, wide kerf type cutting machine, is enabled to cut a full depth slot in the coal face, the cutter blade being extremely narrow so that the slot formed by the cutter blade is of less than half the usual standard kerf width, and, due to the narrow machine width requiring much less space at the coal face and enabling closer roof propping to the face. A still further object of this invention is to provide an improved longwall type floor cutter having improved flexible feeding means. Still another object is to provide a compact and durable coal mining machine of the longwall, floor cutter type capable of being easily maneuvered and having improved slot forming means adjustable to cut superimposed, horizontal, full depth slots in the coal face, in a rapid and efficient manner. A still further object is to provide in a coal mining machine of the above character, improved cutter blade mounting and adjusting means, and improved means for swinging the cutter blade and for locking the latter in adjusted position. These and other objects and advantages of the invention will hereinafter more fully appear in the course of the following description, and as more particularly pointed out in the appended claims.

In the accompanying drawings there is shown for purposes of illustration one form which the invention may assume in practice.

In these drawings,—

Fig. 1 is a plan view of the illustrative embodiment of the improved coal mining machine. 5

Fig. 2 is a side elevational view of the coal mining machine shown in Fig. 1.

Fig. 10 is a detail sectional view showing a portion of the feed drive.

Fig. 11 is a cross sectional view taken substantially on line 11—11 of Fig. 2.

Fig. 12 is a detail sectional view taken on line 12—12 of Fig. 11. 30

In this illustrative embodiment of the invention there is shown a coal mining machine of the continuous cutter, flexibly fed, floor type having an extremely narrow compact frame 1 mounted on a skid plate 2 extending beneath the frame throughout a substantial portion of its length and having a smooth bottom surface 3 adapted to rest upon and slide in any direction over the mine floor. The frame 1 comprises 35

a motor frame section 4 and a front feed frame section 5, the sections 4 and 5 being rigidly united together and rigid with respect to the bottom skid plate. A cutter head 6 is mounted on the rear end of the motor frame section for rotative movement about a horizontal axis extending longitudinally of the machine and has pivotally 40

mounted thereon, on an axis perpendicular to the head axis, an elongated, extremely narrow cutter blade 7. Mounted beneath the front feed frame section 5 is a feed operating member, 45

herein in the form of a haulage drum 8, adapted to cooperate with a flexible feeding element in the form of a wire rope or cable 9. The feed- 50

ing mechanism is adapted to cooperate with the 55

mechanism is adapted to cooperate with the 55

cutter blade and cutter head for swinging the cutter blade with respect to the head and for rotating the head about its axis to position the cutter blade to cut horizontal full depth slots 5 in the coal in superimposed planes, near the level of the mine floor at a substantial distance above the floor level.

The improved slot forming means comprises the rotatable head 6 and cutter blade 7, and this cutter head is journaled on the forward end of the motor frame section for rotation about its axis with respect thereto on a bearing sleeve 10 supported upon a cylindrical bearing support 11 formed on a head member 12 suitably rigidly secured to the front motor head 13, as shown in Fig. 3. The cutter head is provided with an annular flange 14 surrounding a cooperating relatively stationary flange 15 formed on the head 12, and the cutter head is retained in position on its bearing 20 by means of a retaining ring 16 secured, as by screws 17, to the head flange 14, the ring 16 cooperating with the flange 14 to form an annular groove 18 on the cutter head with which the relatively stationary flange 15 cooperates. The 25 means for pivotally mounting the cutter blade 7 on the cutter head 6 comprises a blade hanger 19 mounted on a support member 20 having a bearing hub 21 journaled on bearing sleeves 22 carried by a cylindrical bearing support 23 integral 30 with the cutter head frame. An annular member 23' carried on the lower end of the bearing support 23 cooperates with the lower bearing sleeve to retain the support member 20 in position. Integral with the support 20 is a projection 35 24 having secured thereto, as by screws 25, a segmental retaining plate 26, the projection 24 and plate 26 cooperating to form a groove 27 within which projects an arcuate guide flange 28 formed on the cutter head frame.

40 Now referring to the cutter driving means, it will be noted that the motor frame section 4 contains a motor, herein preferably of the reversible electric type, having its power shaft 29 horizontally disposed and extending longitudinally of the 45 machine in coincidence with the cutter head axis, and the rear end of this power shaft has splined thereto at 30 a sliding clutch member 31 having internal clutch teeth 32 connectible to external clutch teeth 33 formed on a clutch member 34 50 fixed to a shaft 35. The sliding clutch member 31 is operated by a clutch shipper yoke 36 slidably mounted and guided on a pin 37 threadedly secured at 38 with the adjacent wall of the rear motor head 13. Engaging a slot 39 in the hub 55 of the clutch shipper yoke 36 is a projection 40 formed on a lever 41 integral with a clutch operating shaft 42 suitably rotatably mounted in the frame of the head 12. Fixed to the shaft 42 is a hub 43 carrying a pivoted operating lever 44. 60 For locking it in its different positions of adjustment, the lever 44 is provided with an opening 45 engageable, when the lever is swung inwardly, with locking pins 46 secured to the adjacent side of the head frame.

65 Again referring to the cutter blade driving means, it will be noted that the shaft 35 is aligned with the head axis and is suitably journaled within the cylindrical bearing 11 for the head 12 and has fixed thereto at its rear end a bevel gear 48 meshing with a large bevel gear 49. This gear 49 is connected through a friction slip clutch 50, set to slip upon a predetermined overload of the cutter blade, to a shaft 51 arranged with its axis 70 coincident with the pivotal axis of the cutter 75

blade and suitably journaled in the cutter head frame. Secured to this shaft is a chain sprocket 52 adapted to engage and drive the cutter chain 53 guided on the margin of the cutter blade for circulation thereabout. This cutter chain may be of a design similar to that disclosed in my co-pending application Ser. No. 683,328, filed Aug. 2, 1933, now Patent No. 2,048,702.

The cutter blade 7 is swingable into different positions with respect to the cutter head 6 and the means for locking the cutter blade in its different adjusted positions comprises a slidable locking pin 54 guided in a bore 55 formed within a boss 56 integral with the cutter head frame and having an operating rod 57. The outer end of this operating rod is guided in a bore 58 formed in a projection integral with the cutter head frame and the locking pin is constantly urged towards its locking position by means of a coil spring 59 interposed between the projection 58 and the outer end of the locking pin. Secured to the outer end of the operating rod 57 is a swiveled operating handle 60 engageable, when the locking pin is in its released position, with a projection 61 formed on the head frame for holding the locking pin in such released position. This locking pin is engageable with radially located openings 62 suitably spaced about the cutter blade support 20 so that when any one of these openings registers with the bore 55 the locking pin 54 may be slid inwardly into said opening to lock the cutter blade in position. If desired the lock may be released prior to blade swing so when one of the openings registers with the bore 55, the spring 59 will automatically move the pin into locking position.

The means for locking the cutter head in its adjusted positions about its axis comprises a locking pin 64 mounted in a bore 65 formed in the head flange 14 and having an operating rod 66 guided in the head 67 of a tubular member 68 threadedly secured to the head flange 14. A coil spring 69 interposed between the head 67 and the pin 64 normally urges the latter toward its locking position. Secured to the rod 66 is an operating lever 70. The head 12 is provided with spaced openings 71 with which the locking pin is engageable for locking the cutter head in position, the locking pin moving automatically into locking position when the bore 65 is brought into registry with one of the openings 71.

Improved means is provided for adjusting the cutter blade with respect to the cutter blade support 20 and comprises parallel guideways 74, 74' formed by guide flanges 75 secured to the outer surface of the support 20; and slidably mounted in these guideways are the lateral edges of a plate 76 to which the hanger 19 is permanently secured. The plate 76 is provided with an elongated central opening 77 for permitting sliding movement of the plate 76 in its guideways with respect to the support 20, the opening 77 permitting sliding movement of the plate 76 with respect to the bearing hub 21 of the pivotal mounting for the cutter blade support. The means for adjusting the plate 76 with respect to the support 20 comprises a screw 78 mounted at 79 within a pin 80 seated in an opening 81 formed in the support 20. The screw 78 extends through an opening 82 formed in a portion 83 of the plate 76, and engaging the opposite ends of the member 83 and threadedly connected to the screw 78 are adjusting nuts 84, 84'. By adjusting the nuts with respect to the screw, the plate 76 may be slid with respect to the cutter blade support to 75

vary the position of the cutter blade with respect to the chain sprocket axis, thereby to enable a variation in the tightness of the cutter chain.

Now referring to the machine feeding means, it will be noted that fixed to the forward end of the motor power shaft 29 is a spur pinion 86 meshing with spur planet gears 87 journaled on pins 88 carried by a rotatable spider 89 fixed to a shaft 90. Journaled on the hub of a bearing retaining plate 91 secured to the adjacent end wall of the motor frame and on a bearing supported by the hub of the spider 89 is a rotatable reaction member 92, the planet gears 87 meshing with the teeth of an internal gear 93 secured to this reaction member. Engaging a circumferential groove 94 formed circumferentially on the exterior periphery of the reaction member surrounding the internal gear is a brake band 95 having suitable lever operating means 96 actuatable by an adjustable control lever 97 fixed to an operating rod 98. Secured to the rod 98 in a convenient location at the forward end of the machine is a control lever 99. By suitable adjustment of the brake band 95 the reaction member 92 may be held stationary or may be allowed to slip, as desired, thereby to provide a variable speed drive between the motor power shaft and the shaft 90. This shaft 90 is suitably journaled in the feed frame and is arranged with its axis coincident with the power shaft axis and has fixed thereto and drives a worm 101. Meshing with the worm 101 at the opposite sides thereof are worm wheels 102 and 103 arranged on parallel vertical axes spaced equi-distantly from the longitudinal vertical center of the machine and lying in a vertical plane extending transversely of the machine. These worm wheels rotate in opposite directions and are keyed to parallel vertical shafts 104 and 105 suitably journaled in a feed frame section 5. As shown in Fig. 9, keyed to the lower end of the vertical shaft 104 is a spur pinion 106 which constitutes the terminal high speed driving pinion adapted to mesh with a large spur gear 107 secured by screws 108 to the upper flange 109 of the haulage drum 8, this drum being rotatable on a vertical axis and arranged with its lower portion in horizontal planes adjacent the top surface of the bottom skid plate 2 in a haulage drum space 110 formed in the feed frame section. Fixed to the vertical shaft 105 is a spur pinion 111 meshing with a spur gear 112 fixed to a vertical shaft 113 arranged parallel with the shaft 105 and likewise journaled in the feed frame section. Fixed to the lower end of the shaft 113 is a spur pinion 114 which constitutes the terminal low speed driving pinion adapted to mesh with the teeth of the drum driving gear 107. As shown most clearly in Fig. 4, the hub 116 of the haulage drum is journaled on bearing sleeves 117 supported by an eccentric shaft portion 118 of a vertical shaft 119. The shaft 119 is arranged with its axis offset from and parallel to the drum axis and is rotatably mounted in bearing sleeves 120 supported by the feed frame section and bottom skid plate, respectively. Fixed to the upper end of the shaft 119 is a hub 121 of an operating lever 122, this lever being pivotally connected at 123 to the hub 122 and swingable in a vertical direction into locking recesses 124 formed in the locking flange 125 secured to the feed frame section. This flange has three locking recesses for locking the haulage drum in its neutral, high and low speed positions. The shaft 119 may be rotated by the lever 122 to rotate the eccentric

shaft 118 thereby to swing the drum driving gear 107 into meshing engagement with either the high speed terminal gear 106 or the low speed terminal gear 114 of the high and low speed driving means, and when the gear 107 is swung into its intermediate position, it is out of meshing engagement with both the terminal gears 106 and 114. It will thus be seen that the haulage drum may be driven at either a relatively high predetermined machine moving speed, a relatively low predetermined cutting speed and through a wide range of variable high and low speeds under the control of the planetary slip device 92, 95. Journaled on the feed frame section on vertical axes spaced equi-distantly from the longitudinal vertical center of the machine and lying in a transverse vertical plane to the rear of the haulage drum axis are guide sheaves 130, 130 for guiding the haulage cable 9 with respect to the haulage drum. The haulage cable may be extended from the haulage drum about either of these guide sheaves and extended along the coal face to a suitable anchor, and when the haulage drum is rotated to wind in the haulage cable the machine is fed over the mine floor bodily along the coal face.

The haulage cable 9 and haulage drum are also employed for swinging the cutter blade 7 and for rotating the cutter head 6. Journaled on axes inclined with respect to the horizontal at the opposite sides of the machine frame with their axes lying in a transverse vertical plane to the rear of the rear motor head between the latter and the cutter head flange 14 are guide sheaves 131, 131, while formed on the cutter blade projection 24 is an arcuate guiding groove 132, and projecting from the support 20 at spaced points are cable abutments in the form of eyes 133 each having an opening 134. When it is desired to swing the cutter blade 7 about its pivot with respect to the cutter head, the haulage cable 9 is extended about one of the guide sheaves 130, then extended rearwardly along the side of the machine frame about the guiding groove 132 and connected by a suitable hook 135 secured to the free end of the haulage cable to the opening 134 in one of the projections 133 integral with the cutter blade support 20. The locking pin 54 is then released, and upon rotation of the haulage drum 8 the haulage cable 9 is wound in to effect swinging of the cutter blade about its pivot. The cutter blade is locked in the desired adjusted position by the locking pin 54. When it is desired to effect rotation of the cutter head 6, the haulage cable is extended around one of the guide sheaves 130 rearwardly along the side of the machine around one of the guide sheaves 116 then upwardly around a guiding groove 136 formed externally about the flange 14 of the cutter head frame and the hook 135 on the haulage cable is connected to a pin or other suitable abutment 137 secured to the cutter head frame. The cutter head locking pin 71 is then released, and upon rotation of the haulage drum 8 to wind in the haulage cable 9 the cutter head 6 is rotated about its axis. When the bore 65 is brought into registry with an opening 71 the locking pin 64 is moved automatically into locking position by the coil spring 69. It will be evident that by a rearrangement of the haulage cable with respect to the drum and the various guide sheaves the cutter blade may be swung and the cutter head rotated in the opposite direction and the machine propelled in the opposite direction.

As the operation of a longwall coal cutting machine is well known to those skilled in the art, a description of the mode of operation of the machine is considered unnecessary other than to state that the cutter blade is swung about its pivot into sumping position beneath the coal, locked in such position and thereafter the machine is fed bodily along the coal face to effect the cutting of a horizontal slot in the coal. The machine is moved rapidly over the mine floor at a high machine moving speed during maneuvering of the machine and is fed along the coal face at a relatively low cutting speed during the cutting operation, and during either of these operations either feeding speed may be varied at will by the planetary slip control device. By the provision of a rotatable cutter head, horizontal slots may be cut in the coal face in superimposed relation, near the level of the mine floor and a substantial distance above the floor level. These and other uses and advantages of the improved coal mining machine will be clearly apparent to those skilled in the art.

While I have in this application specifically described one form which my invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In a coal mining machine, a machine frame adapted to rest upon and slide in any direction over the mine floor, a cutter head mounted on said frame for rotation with respect thereto about a horizontal axis extending longitudinally of the machine, a cutter blade pivotally mounted on said cutter head to swing relative thereto, and motor operated means for rotating said cutter head, for swinging the cutter blade about its pivot, and for feeding the machine over the mine floor, said feeding means including a feeding element connectible to said cutter head and cutter blade for effecting rotation of said head and swinging of said cutter blade and connectible extraneously of the machine to effect feed of the latter.

2. In a coal mining machine, a machine frame adapted to rest upon and slide in any direction over the mine floor, a cutter head mounted on said frame for rotation with respect thereto about a horizontal axis extending longitudinally of the machine, a cutter blade pivotally mounted on said cutter head to swing relative thereto, and motor operated means for rotating said cutter head, for swinging the cutter blade about its pivot, and for feeding the machine over the mine floor, said motor operated feeding means including a feeding element on the machine with which a flexible feeding element cooperates, the latter also connectible either to the head or the cutter blade to effect head rotation and cutter blade swing.

3. In a coal mining machine, a machine frame adapted to rest upon and slide in any direction over the mine floor, a cutter head mounted on the rear end of said frame for rotation with respect thereto about a horizontal axis extending longitudinally of the machine, a cutter blade pivotally mounted on said cutter head to swing relative thereto, and motor operated means for rotating the cutter head, for swinging the cutter blade about its pivot, and feeding the machine

over the mine floor, said feeding means including a feeding element connectible to said cutter head and said cutter blade for effecting rotation of said head and swinging of said cutter blade and connectible extraneously of the machine to effect feed of the latter.

4. In a coal mining machine, a machine frame adapted to rest upon and slide in any direction over the mine floor, a cutter head mounted on the rear end of said frame for rotation with respect thereto about a horizontal axis extending longitudinally of the machine, a cutter blade pivotally mounted on said cutter head to swing relative thereto, and motor operated means for rotating the cutter head, for swinging the cutter blade about its pivot, and feeding the machine over the mine floor, said motor operated feeding means including a feeding element on the machine with which a flexible feeding element cooperates, the latter also connectible either to the head or the cutter blade to effect head rotation and cutter blade swing.

5. In a coal mining machine, a machine frame adapted to rest upon and slide in any direction over the mine floor, a cutter head mounted on the one end of said frame and rotatable with respect thereto about a horizontal axis extending longitudinally of the machine, a cutter blade pivotally mounted on said cutter head to swing relative thereto, and motor operated means arranged at the opposite end of the machine frame for feeding the machine over the mine floor and including a feeding element connectible to the head and cutter blade for swinging the cutter blade about its pivot and for rotating the cutter head and connectible extraneously of the machine to effect feed of the latter.

6. In a coal mining machine, a machine frame adapted to rest upon and slide in any direction over the mine floor, a cutter head mounted on the one end of said frame and rotatable thereto about a horizontal axis extending longitudinally of the machine, a cutter blade pivotally mounted on said cutter head to swing relative thereto, and motor operated means arranged at the opposite end of the machine frame for swinging the cutter blade about its pivot, for rotating the cutter head and for feeding the machine over the mine floor, said motor operated feeding means including a power feeding element on the end of the machine frame opposite from the cutter head and with which a flexible feeding element cooperates, said flexible feeding element being extendible longitudinally of the machine frame for connection to either the cutter head or cutter blade to effect head rotation and cutter blade swing.

7. In a coal mining machine, a machine frame adapted to rest upon and slide in any direction over the mine floor, a cutter head mounted on said frame for rotation with respect thereto about a horizontal axis extending longitudinally of the machine, a cutter blade pivotally mounted on said cutter head to swing relative thereto, flexible feeding means for the machine including a feed operating member with which a flexible element cooperates, and means on the machine for guiding said flexible element into a position for engagement with the cutter head, said feeding element being actuatable by said feed operating member to effect head rotation.

8. In a coal mining machine, a machine frame adapted to rest upon and slide in any direction over the mine floor, a cutter head mounted on said frame for rotation with respect thereto

about a horizontal axis extending longitudinally of the machine, a cutter blade pivotally mounted on said cutter head to swing relative thereto, flexible feeding means for the machine including 5 a feed operating member with which a flexible element cooperates, means on the machine for guiding said flexible element into a position for engagement with the cutter head, said feeding element being actuatable by said feed operating 10 member to effect head rotation, and means associated with the cutter blade to which said flexible element is connectible for effecting swinging of the cutter blade.

9. In a coal mining machine, a machine frame 15 adapted to rest upon and slide in any direction over the mine floor, a cutter blade on said frame, and motor operated means for feeding the machine over the mine floor including a feed operating member on said frame adapted to 20 cooperate with flexible feeding means, motor operated means for effecting rotation of said feed operating member at either a predetermined high speed or a predetermined low speed and including high and low speed terminal driving elements 25 rotating on axes lying in a vertical plane extending transversely of the machine, and means associated with said high and low speed driving means for effecting a variable speed during drive at either speed and including a variable speed device having a variable speed terminal 30 driving element through which said predetermined high and low speed rotating means are driven.

10. In a coal mining machine, a machine frame 35 adapted to rest upon and slide in any direction over the mine floor, a cutter blade on said frame, and motor operated means for feeding the machine over the mine floor including a feed operating member on said frame adapted to 40 cooperate with flexible feeding means, motor operated means for effecting rotation of said feed operating member at either a predetermined high speed or a predetermined low speed and including high and low speed terminal driving elements 45 rotating on axes lying in a vertical plane extending transversely of the machine, and means associated with said high and low speed driving means for effecting a variable speed during drive at either speed and including a frictionally controlled planetary variable speed device 50 having a variable speed terminal driving element through which both high and low speeds are driven.

11. In a mining machine, cutting means, and 55 feeding means for said cutting means including a predetermined high speed driving means having a terminal driving element, a predetermined low speed driving means having a terminal driving element, a feed operating member adapted 60 to cooperate with flexible feeding means, a gear for rotating said feed operating member, and means for moving said gear selectively into driving engagement with either of said terminal driving elements.

65 12. In a mining machine, cutting means, and feeding means for said cutting means including a high speed driving means having a terminal driving element, a low speed driving means having a terminal driving element, a feed operating member adapted to cooperate with flexible 70 operating means, a gear for rotating said feed operating member, and means for moving said gear selectively into driving engagement with either of said terminal driving elements and in-

cluding an eccentric mounting means for said gear.

13. In a mining machine, cutting means, and means for feeding said cutting means including a motor having its power shaft extending longitudinally of the machine with its axis lying in the longitudinal vertical center of the machine, a planetary variable speed device driven by said motor and having a variable speed terminal driving element, said device arranged with its axis alined with the motor power shaft axis, a predetermined high speed gear train, a predetermined low speed gear train, said trains driven by said motor through the terminal driving element of said variable speed device, a 10 feed operating member adapted to cooperate with the flexible feeding means, and means for moving said feed operating member selectively into driving engagement with either said high speed train or said low speed train. 20

14. In a mining machine, cutting means, and means for feeding said cutting means including a motor having its power shaft extending longitudinally of the machine with its axis lying in longitudinal vertical center of the machine, a 25 planetary variable speed device driven by said motor and arranged with its axis alined to the motor power shaft axis, a shaft coaxial with said variable speed device and driven thereby, a gear fixed to said shaft, a fast speed gear 30 train driven by said gear, a low speed gear train driven by said gear, a feed operating member adapted to cooperate with flexible feeding means, and means for moving said feed operating member selectively in engagement with said 35 high and low speed gear trains.

15. In a mining machine, cutting means, and means for feeding said cutting means including high and low speed driving gearing, each gearing having a terminal driving element individual 40 thereto, a feed operating member adapted to cooperate with flexible feeding means and an eccentric mounting for said feed operating member whereby the latter may be moved selectively into driving engagement with said terminal driv- 45 ing elements.

16. In a mining machine, cutting means, and means for feeding said cutting means including a motor, a variable speed planetary device having a variable speed terminal driving element and arranged with its axis horizontal and extending longitudinally of the machine midway between the sides of the machine, a high speed gear train, a low speed gear train, said gear trains driven by said motor through the 55 terminal driving element of said variable speed device and including high and low speed terminal driving elements rotating on axes lying in a vertical plane extending transversely of the machine, a feed operating member adapted to 60 cooperate with flexible feeding means, and means for connecting said feed operating member selectively into driving relation with said gear trains.

17. In a mining machine, cutting means, and means for feeding said cutting means including a motor, a planetary variable speed device arranged with its axis horizontal and extending longitudinally of the machine midway between the sides of the machine, a shaft coaxial with 70 said variable speed device and driven thereby, a worm fixed to said shaft, a high speed gear train including a worm wheel meshing with said worm and having a high speed terminal driving element, a low speed gear including a 75

worm wheel meshing with said worm and having a low speed terminal driving element, a feed operating member adapted to cooperate with flexible feeding means, and a gear connected in driving relation to said feed operating member and mounted to move selectively into driven engagement with said high and low speed elements.

18. In a mining machine, cutting means, and means for feeding said cutting means including a feed operating member adapted to cooperate with flexible feeding means, high speed driving means including a high speed terminal driving element, low speed driving means including a low speed terminal driving element, a driving element rotatable with said feed operating member, and means for adjusting the position of the latter to move the driving element connected thereto selectively into driven relation with either of said high and low speed driving elements.

19. In a mining machine, a machine frame adapted to rest upon and slide in any direction over the mine floor, a cutter head mounted on said frame for rotation about a horizontal axis extending longitudinally of said frame, a kerf cutter carried by said cutter head, flexible feeding means for the machine including a feed operating member on the frame and with which a flexible feeding element cooperates, and means on the machine for guiding said flexible feeding element into a position for engagement with the cutter head, said feeding element being actuatable by said feed operating member to effect head rotation.

20. In a mining machine, a machine frame, a cutter head mounted on said frame for rotation with respect thereto about a horizontal axis extending longitudinally of the machine, a kerf cutter carried by said cutter head, and motor operated means for feeding the machine during the cutting operation and including a feeding element alternatively cooperant directly with means extraneous to the machine to effect feed or connectible to said cutter head and actuatable then to effect head rotation.

21. In a mining machine, a machine frame, a cutter head mounted on said frame for rotation with respect thereto about a horizontal axis extending longitudinally of the machine, a kerf cutter pivotally mounted on said cutter head to swing relative thereto, and motor operated means for feeding the machine during the cutting operation including a feeding element which constitutes the ultimate connection between the machine and extraneous means during feeding and which is also connectible to said cutter head and said kerf cutter and actuatable to effect head rotation and swinging of said kerf cutter.

22. In a mining machine, a machine frame, a cutter head mounted on said frame for rotation with respect thereto about a horizontal axis extending longitudinally of the machine, a kerf cutter pivotally mounted on said cutter head to swing relative thereto, flexible feeding means for the machine including a feed operating member with which a flexible feeding element cooperates, and means on the machine for guiding said flexible feeding element into a position for engagement with the cutter head, said feeding element being actuatable by said feed operating member to effect head rotation.

23. In a coal mining machine, a machine frame, a cutter head mounted on said frame for rotation with respect thereto about a horizontal axis extending longitudinally of the machine, a kerf

cutter pivotally mounted on said cutter head to swing relative thereto, flexible feeding means for the machine including a feed operating member with which a flexible feeding element cooperates, means on the machine for guiding said flexible feeding element into a position for engagement with the cutter head and said kerf cutter, said flexible feeding element being actuatable by said feed operating member to effect head rotation and swinging of said kerf cutter.

24. In a mining machine, cutting means, and feeding means for said cutting means including a high speed driving means having a terminal driving element, a low speed driving means having a terminal driving element, a feed operating member adapted to cooperate with flexible feeding means, a gear for rotating said feed operating member, and means for moving said gear selectively into driving engagement with either of said terminal driving elements and including a swingable mounting means for said gear.

25. In a mining machine, cutting means, and means for feeding said cutting means including a motor having its power shaft extending longitudinally of the machine with its axis lying in the longitudinal vertical center of the machine, a planetary variable speed device driven by said motor and having a variable speed terminal driving element and arranged with its axis lying in the longitudinal vertical center of the machine, a predetermined high speed gear train, a predetermined low speed gear train, said trains driven by said motors through the terminal driving element of said variable speed device, a feed operating member adapted to cooperate with flexible feeding means, and means for moving said feed operating member selectively into driving engagement with either said high speed gear train or said low speed gear train.

26. In a mining machine, a machine frame adapted to rest upon and slide in any direction over the mine floor, a cutter head mounted on said frame for rotation with respect thereto about a horizontal axis extending longitudinally of the machine, a kerf cutter mounted on said cutter head, and motor operated means for rotating said cutter head and for feeding the machine over the mine floor, said head rotating means including an annular guiding portion secured to said cutter head and said motor operated feeding means including a feeding element on the machine with which a flexible feeding element cooperates, the latter connectible to said cutter head and engageable with said guiding portion for effecting head rotation.

27. In a mining machine, a machine frame adapted to rest upon and slide in any direction over the mine floor, a cutter head mounted on said frame for rotation with respect thereto about a horizontal axis extending longitudinally of the machine, a kerf cutter pivotally mounted on said cutter head to swing relative thereto, and motor operated means for rotating said cutter head, for swinging said kerf cutter about its pivot and for feeding the machine over the mine floor, said cutter head rotating means including an annular guiding portion secured to said head, said kerf cutter swinging means including an arcuate guiding portion secured to said kerf cutter, and said motor operated feeding means including a feeding element on the machine with which a flexible feeding element cooperates, said flexible feeding element connectible either to said cutter head or said kerf cutter and engageable with

said annular guiding portion on said head or said arcuate guiding portion on said kerf cutter to effect head rotation and kerf cutter swing.

28. In a mining machine, a base adapted to 5 rest upon and slide in any direction over the mine floor, a kerf cutter, means for pivotally supporting said kerf cutter on said base for swinging movement with respect thereto about rectangularly related axes, and flexible feeding means 10 for the machine for moving the latter bodily over the mine floor including a rotatable actuator on said base and a flexible element cooperating directly with said actuator and adapted for connection to an extraneous abutment, said flexible 15 element connectible to said supporting means and actuatable by said actuator for swinging said kerf cutter about said rectangularly related axes.

29. In a mining machine, a base adapted to rest upon and slide in any direction over the mine floor, a kerf cutter, means for pivotally supporting said kerf cutter on said base for swinging movement with respect thereto about 5 rectangularly related axes, one of which is horizontally disposed and extends longitudinally of said base, and flexible feeding means for the machine for moving the latter bodily over the mine floor including a rotatable actuator on said base 10 and a flexible element cooperating directly with said actuator and adapted for connection to an extraneous abutment, said flexible element connectible to said supporting means and actuatable by said actuator for swinging said kerf cutter 15 about said rectangularly related axes.
